United States Patent Office.

HAYDN M. BAKER, OF HARLEM, NEW YORK.

Letters Patent No. 80,381, dated July 28, 1868.

IMPROVEMENT IN CLEANING COTTON-WASTE.

The Schedule referred to in these Letters Patent and making part of the same.

TO ALL WHOM IT MAY CONCERN:

Be it known that I, HAYDN M. BAKER, of Harlem, in the city, county, and State of New York, have invented a new and useful Process for "Cleaning Cotton-Waste and recovering oils from the same;" and I do hereby declare that the following is a full and exact description thereof.

The nature of my invention consists in removing oils from cotton-waste, by dissolving said oils with coal-tar-benzole or coal-tar naphtha while the said cotton-waste is immersed in the same, making use, at the same time, of any mechanical appliance which will procure and communicate alternate motion, agitation, and compression to the benzole or naphtha and cotton-waste during the term of immersion.

The next stage consists in removing the solution of oils from the cotton-waste and conveying them to a distillatory apparatus, observing to press the cotton-waste by any suitable mechanical appliance, to disengage and separate the solution of oils.

The cotton-waste dried is ready for use again.

The next stage consists in separating the coal-tar benzole or naphtha from the oils by distillation.

To enable others to make use of my invention, I will proceed to describe it more particularly.

I place any amount of saturated cotton-waste in a vessel, (capable of being made tight,) with sufficient benzole or naphtha to effect a complete solution of all the oils contained therein, and then run off said solution into a distillatory apparatus, and submit same to distillation at a low temperature, or at such temperatures as will disengage and distil over the benzole and naphtha from the oils.

The benzole and naphtha, or mixtures of each, may be used repeatedly.

The cotton-waste may be pressed and dried, and then washed with a weak solution of soap or alkalies, and again dried, when it will be found to be perfectly clean, and with an uninjured fibre.

The advantage of this invention is, that it provides an economical method of cleaning cotton-waste, and recovering the oils contained therein, without injury to the fibre of said cotton-waste.

Claim.

What I claim as my invention, and desire to secure by Letters Patent, is—

The use of coal-tar benzole or coal-tar naphtha, or mixtures of same, and their equivalents, for removing oils from cotton-waste, (or other fibre used for similar purposes,) and also the separation and recovery of the oils and solvents by distillation.

HAYDN M. BAKER.
